(57) **CLAIM**

I claim the ornamental design for a latch housing, as shown and described.

DESCRIPTION

T-Handle (U.S. Design Patent Application)

T-Handle Assembly (U.S. Design Patent Application)

FIG. 1 is an top plan view of a latch housing showing my new design;

FIG. 2 is a top perspective view thereof;

FIG. 3 is a left side elevational view thereof;

FIG. 4 is a right side elevational view thereof;

FIG. 5 is a front elevational view thereof; and,

FIG. 6 is a rear elevational view thereof.

The broken lines next to shade lines form the boundary of the claimed design. Other broken lines illustrate the disclaimed portions of the design. None of the broken lines form part of the claimed design.

1 Claim, 4 Drawing Sheets
